HYGROSCOPIC ELEMENT FOR INDICATORS
AND THE LIKEWorth C. Goss, Seattle, Wash., assignor to
Humidity Control Company

Application June 13, 1931, Serial No. 544,244

10 Claims. (Cl. 297—1)

This invention relates to improvements in indicating and controlling elements especially useful in connection with indicating and controlling instruments which operate under influence of 5 and in accordance with changes of relative humidity of the surrounding air; it being the principal object of this invention to provide a hygroscopic indicating element for instruments of the above character having an improved form of 10 construction which eliminates the possibility of the parts constituting the element being subjected to undue strain by reason of unequal expansion or contraction which would cause inaccuracy and finally necessitate a recalibration. Another 15 object is to provide a method of treating the hygroscopic material of the element to greatly increase its sensitivity.

Explanatory to the present invention, it will be explained that heretofore instruments of this 20 character, in general, have employed an indicating or controlling element made up of two strips of flexible materials glued or otherwise fixed together, preferably in accordance with disclosures of my co-pending application Serial No. 493,804, filed November 6, 1930, for an improvement in 25 hygrostatic control; one of these strips being a material which will contract and expand in length in accordance with changes of humidity to a greater extent than the other strip, thus to cause 30 the element to bend one way or the other to indicate the degree of any change or to actuate a control switch, or the like. It has been customary to employ two strips of wood or other equivalent materials for this purpose, and to glue the strips 35 firmly together; the wooden strips in this instance having different characteristics or properties causing them to be differently affected by atmospheric conditions and to thus cause the instrument to function. Elements of this type of 40 construction operate with a satisfactory degree of accuracy only within certain limits, and then will give satisfactory results only so long as the hygroscopic materials are not subjected to strain beyond their elastic limits. However, to keep 45 within safe limits would be to so restrict the utility of the instrument that it would be undesirable for practically all commercial purposes, since any indicator or controller so constructed, to be commercially desirable, must be able to indicate 50 correctly the usual variation of relative humidity from one to ninety per cent.

The undesirability of those types of indicators which have the hygroscopic parts thereof glued together, as above stated, is due to the fact that 55 with every change in relative humidity opposing

strains or stresses are set up in the strips along the connected surfaces by reason of one of the strips expanding or contracting to a greater extent than the other, and this strain places a limitation on the range of the instrument. It 5 is readily apparent that when the strips are glued tightly together, their attached surfaces cannot move relative to each other, and thus one strip along its glued surface is placed under tension and the other strip along the glued surface is 10 placed under compression. These opposing strains on the strips are in accordance with the degree of change of humidity and should either piece be stressed beyond its limit of elasticity permanent "case hardening" or "set" in the element will be the result and the piece will not 15 again assume its original position for any certain degree of relative humidity. This would necessitate a readjustment and change of calibration in order to give correct readings. 20

Test and experiment have shown that practically all of such indicators become inaccurate after short use and this is due primarily, or for the most part by reason of stressing the parts 25 to an extent that they will not return to their original setting.

In view of this above stated undesirable result in indicating and controlling instruments, as previously made, it has been the object of this invention to provide an instrument for indicating 30 or for controlling, and which will operate accurately under all conditions of relative humidity and will accurately accommodate the full range for an indefinite period of time without any material change in its original calibration. 35

More specifically stated, the present invention resides in the provision of an indicator or controller element in which the two complementary strips of material or materials which cause functioning of the element are connected by an interposed, elastic member which permits of movement of one strip relative to the other in accordance with humidity changes, yet holds them firmly and securely in proper functional relationship, without causing any detrimental strain 45 to be placed on either strip regardless of their degree of flexure; that is, a connecting strip that insures against straining the strips beyond their elastic limit.

It is also an object of the invention to produce 50 a hygroscopic element that is well adapted for use in various kinds of instruments, both for indicating or for controlling, which operate in accordance with and under control of atmospheric changes. 55

It is also an object of this invention to provide an instrument for indicating atmospheric conditions and which is of novel construction, and embodies as the principal parts thereof an indicating element made in accordance with the present invention, and a thermometer.

In accomplishing these and other objects of the invention, I have provided the improved details of construction, the preferred forms of which are illustrated in the accompanying drawing, wherein—

Fig. 1 is a front view of an instrument embodying improved details of construction according to the present invention.

Fig. 2 is a vertical cross section taken on line 2—2 in Fig. 1.

Fig. 3 is a front view of the hygroscopic element as mounted on a support within the instrument.

Fig. 4 is an enlarged longitudinal section of a portion of the hygroscopic element.

Fig. 5 is a cross section of the same.

Fig. 6 is a perspective view illustrating an alternative form of element, a part being broken out for better illustration.

Fig. 7 is a view illustrating a form of construction for increasing the force of the instrument when used as a controller.

Fig. 8 is a view illustrating a construction for multiplying the movement of the element.

The drawing is intended to illustrate some of the most common, practical uses for the present element and it is not intended that they shall convey the idea that these are the only applications to which it may be put, since it is to be understood that the element is well adapted to all those uses to which other elements of a hygroscopic character have heretofore been applied, or to which they may be applied.

Referring more in detail to the drawing—

1 designates the housing or mounting for the instrument, and it comprises an enclosed compartment 2 over which a back or cover plate 3 is removably fitted. This housing or mounting piece may, if such is desired, be of an ornamental character as shown, or may be of any other suitable form, and it is provided across the top with a forwardly opening window 4 of arcuate form, back of which a dial plate 5 is supported, there being an open space as at 6 between the plate and the front wall of the housing for the movement therein of an indicator hand or pointer, as will presently be described, which co-operates with marked graduations, as at 7 on the plate, whereby the relative humidity will be indicated. The indicating mechanism comprises the hand or pointer 8 which is pivotally mounted at its lower end by a supporting stud 9 that is fixed in a bearing or support 10 carried on the inner face of the cover plate 3 near its lower edge. The pointer is directed upwardly within the housing and has an outwardly offset end portion extending through the open space 6 for travel along the forward side of the graduated dial plate. In the lower end portion of the pointer is a longitudinally extending slot 12 within which a pin 13, that is fixed in the lower end of a hygroscopically actuated element 15, is operable to cause movement of the pointer in accordance with the movement of the element to thus indicate, by reference to the graduations on the dial plate, the changes in relative humidity of the atmosphere.

A novel feature of this invention resides in the construction of the hygroscopic element desig-

nated in its entirety by reference character 15. The element consists of two flexible strips 16 and 17 of material, and these are glued, cemented or otherwise attached to the surfaces of an interposed strip 18 of a flexible, elastic material such as rubber, cork, or the like. In some instances it may be desirable to connect the parts by rivets extended through the rubber or by the other means of attachment which would permit of the desired flexing and relative movement of parts without any functional interference.

The interposed strip 18 preferably would be continuous, but it is to be understood that satisfactory results might also be obtained by use of short sections 18' at spaced intervals along the element as shown in Fig. 6. These should not be spaced so far as to nullify the action of the element by reason of relative longitudinal movement. One of these outer strips must be hygroscopic, and one only partially or preferably non-hygroscopic.

It has been found most practical to employ strips of wood for the outer side portions of the element and to glue them securely to the opposite surfaces of a strip of rubber. Very satisfactory results have been obtained by use of a strip of eastern hard maple on one side of the element of end grain cut to expose the open pores to the atmosphere to render it more sensitive. The other side strip is very satisfactory when made of western red cedar of longitudinal cut so as to be affected to the least possible extent by atmospheric changes. Also this latter strip may be painted to increase its resistance to atmospheric changes. Tests have shown that the maple strip will change 10% in length with a change in moisture content from 1% to 25% while the cedar will change .01% in length for a like change in moisture conditions.

As a matter of explanation, it will here be stated that by "end grain cut" is meant a strip wherein the direction of grain is directly through the strip from face to face. This would mean that the pores of the strip will open to the flat inner and outer faces of the strip. By "longitudinal cut" is meant that the fiber forming the grain extends lengthwise of the strip, thus the pores would extend lengthwise and would not open to atmosphere except at the ends of the strip.

These two strips, after being attached or applied to the interposed rubber strip, are fixed rigidly at one end to a block 20 fastened centrally to the upper edge of the cover plate 3 with the stud or pin 13 at the lower end of the element extended into the slot in the lower end portion of the pointer.

Assuming the element to be so constructed and applied in use as in Fig. 1, it is quite apparent that with the element exposed to the atmosphere, changes in relative humidity will cause expansion and contraction of one of the strips to an extent more or less than the other, and this will have the effect of bending the free end of the element laterally in one direction or the other. This movement, through the medium of the connecting pin 13, will cause the pointer to move accordingly. Thus by reference to the graduated scale, the relative humidity at any time may be ascertained. It is further apparent that regardless of the extent to which the element is flexed in one direction or the other, there will be no detrimental strain or stress on either of the strips, for the reason that flexibility of the interposed strip of rubber permits movement of one strip relative to

the other and still retains them functionally connected.

It is to be understood that I do not wish to confine the element to the use of wooden strips or to the use of a rubber connecting and cushioning strip, for it is quite possible to satisfactorily employ other hygroscopic materials in a like manner. For instance, a strip of wood in connection with a flexible metallic strip may serve the purpose, so long as there is an interposed element which will operate to the same purpose as the rubber, such as cork or any other elastic material; the best results being obtained however when the interposed, elastic element is non-hygroscopic.

15 In the present drawing, in Figs. 1 and 2, I have disclosed an instrument for indicating atmospheric conditions, that is, the relative humidity of the atmosphere and also the temperature. In such instruments it is not sufficient to provide only for indicating the relative humidity of the atmosphere, for the reason that a certain relative humidity which may be healthful at one temperature will not be healthful at another temperature. To determine proper air conditions one should know not only the condition of the atmosphere with respect to humidity, but also with respect to its temperature. Therefore, for convenience, a thermometer 24 is mounted in a vertical opening 25 in the front wall of the housing upon a panel 26. Thus when a reading of the upper dial is made, notation of the temperature may be made at the same time, and from these readings it may be determined whether or not proper atmospheric conditions exist.

35 Devices of the present character are very desirable for home use so that proper conditions of temperature and humidity may be maintained. However, the instrument is not to be confined to this particular use.

40 In Fig. 7 I have illustrated a form of arrangement for increasing the strength of the instrument, more especially when it is to be used as a controller. In this arrangement I provide a fixed mounting piece 40 of a non-hygroscopic character in which a plurality of elements 15 like those previously described in detail, are fixed, and which extend substantially at a right angle to the mounting piece. At their lower ends these elements are pivotally connected to a link 41 for parallel movement, and the link has a pin 42 at its end for the actuation of a switch, or the like. In this form of arrangement, the power to be derived from the instrument may be increased in accordance with the number and character of elements employed.

55 In Fig. 8 is illustrated an arrangement of elements for multiplying movement of the instrument. In this construction there is a plurality of elements 15 arranged in end to end connection in a series of upright and inverted V's. The first element, 15a, of the series is fixed at its upper end in a block 45. The second element, 15b, is mounted in a block 46 fixed to the lower end of the first element to extend in an upward angular relation to the first. The third element, 15c, of the series is fixed in a block 47 attached rigidly to the upper end of the second element. This arrangement of elements is continued to the extent desired, and the elements are so arranged that the movement of each one is added to that of the other in contraction or expansion.

60 It is further to be understood that the strength of the element is more or less in accordance with the width of the hygroscopic element and the movement dependent also on its length.

As was previously stated, one of the objects of the invention is to treat the hygroscopic material in a novel manner to add to its sensitivity. In a preferred treatment of the wooden strip which controls movement of the element the cell substance is removed to leave the pores open to air, thereby greatly increasing its affected surface. This treatment consists of boiling the wood in water or other suitable material a plurality of times or sufficient that the cell substance is dissolved or washed out from the pores, after which it is properly dried to prevent warping. Wood so treated has been found to be exceedingly more sensitive than untreated wood and therefore is more desirable for instruments of this character. The usual treatment is three separate boilings in fresh water and then an even drying by forcing air evenly across the piece.

15 It is desired to point out that in each and every one of the instruments above described, the efficiency and continued accuracy of the instrument is primarily due to the details of construction of the element or elements 15 employed therein. These elements are featured by the elastic strip or sections interposed between and joining the two complementary outer strips, one of which is of a hygroscopic character and the other preferably non-hygroscopic. It is thought well to point out that the rubber strip used, or its equivalent, should have sufficient stretch lengthwise to permit expansion and contraction of the hygroscopic element to its limits without placing the piece under detrimental strain, and the thickness of the rubber strip also should be so limited that it would not stretch in the direction of its thickness to an extent that the movement of the hygroscopic strip relative to the non-hygroscopic strip would be nullified.

20 Having thus described my invention, what I claim as new therein and desire to secure by Letters Patent is—

1. In an instrument of the class described, a hygroscopic element comprising co-extensive flexible strips joined functionally by interposed elastic means; one of said strips being more sensitive to moisture than the other.

2. In an instrument of the class described, a hygroscopic element comprising co-extensive flexible strips joined throughout their effective lengths by interposed elastic member permitting relative movement of the co-extensive strips in a longitudinal direction; one of said strips being more sensitive to moisture than the other.

3. In an instrument of the class described, an element comprising co-extensive, flexible strips of different character hygroscopically, and elastic means interposed between said flexible strips at spaced points and functionally joining them.

4. In an instrument of the class described, an element adapted to be operated incident to humidity changes and comprising two co-extensive, flexible strips of different hygroscopic character joined together throughout their effective lengths by interposed elastic means permitting lateral flexing of the element and relative longitudinal adjustment of the strips without detrimental strains or stress by reason of the connection.

5. In an instrument of the class described, an element adapted to be actuated incident to humidity changes and comprising two co-extensive, flexible strips, one of which is of hygroscopic nature; said strips being joined throughout their effective lengths by an interposed strip of elastic material of non-hygroscopic character.

6. An element of the class described compris-

ing two co-extensive, flexible strips of different hygroscopic character, and an interposed strip 5 of elastic material with opposite faces cemented to the adjacent faces of said co-extensive strips to functionally join them throughout their effective lengths; said interposed strip being adapted to stretch in its longitudinal direction to accommodate the relative movement of the strips in that direction, but having a negligible amount of 10 stretch in the direction of its thickness.

7. A hygroscopic element comprising co-extensive, flexible strips of materials of different character hygroscopically, and an interposed strip of an elastic material functionally joining said 15 co-extensive strips throughout their effective lengths; said interposed strip being adapted to stretch in a lengthwise direction sufficiently to permit relative longitudinal movement of the strips for the full range of movement but maintaining necessary tension between the strips to cause functioning of the instrument by reason of 20 the relative longitudinal movement.

8. An instrument of the character described including a hygroscopic element fixedly supported at one end and movable in accordance with humidity changes; said element comprising 25 two co-extensive strips of material of different

hygroscopic nature and joined functionally throughout their effective lengths by an interposed strip of an elastic character permitting flexing of the element and relative adjustment of the co-extensive strips without causing detrimental stress or strain by reason of their connection.

9. A hygroscopic element comprising two co-extensive flexible strips joined throughout their effective lengths by an interposed strip of flexible, cushioning material of a non-hygroscopic character permitting relative longitudinal movement of the strips joined thereby without causing harmful stress or strain by reason of the connection; one of said strips being of wood of tangential end grain or radial end grain cut and the other being of wood of longitudinal cut.

10. A hygroscopic element comprising two co-extensive wooden strips of a flexible character, and a strip of rubber interposed between the 20 wooden strips and glued or otherwise attached thereto throughout their effective lengths; one of said wooden strips being of maple wood of radial end grain cut, the other being of cedar wood of longitudinal cut.
